UNITED STATES PATENT OFFICE.

PAUL MEINDEL, OF BROOKLYN, NEW YORK.

FREIGHT-CAR.

1,259,426.

Specification of Letters Patent. Patented Mar. 12, 1918.

Application filed January 26, 1918. Serial No. 213,857.

To all whom it may concern:

Be it known that I, PAUL MEINDEL, a citizen of the United States, and a resident of the borough of Brooklyn, in the county of 5 Kings and city and State of New York, have invented a new and useful Freight-Car, of which the following is a specification.

The object of this invention is to facilitate the loading and unloading of box 10 freight cars. This is accomplished by a construction which throws open the entire side of the car, without, however, involving lateral outboard movement of the parts, which would be prohibitive. The car side is made 15 in upper and lower sections which slide vertically in opposite directions. The sections are connected by cables passing over pulleys, in such manner as to cause their simultaneous movement, the one up and the other down. The upper section is preferably made 20 to overbalance the lower section, so that they tend to close, and a toggle may be provided between the sections to hold them open.

In the drawings:

25 Figure 1 is a side elevation of a freight car embodying the invention;

Fig. 2 is a fragmentary elevation toward one side of the car, showing the side sections open;

30 Fig. 3 is an end view of Fig. 2, indicating how the bottom flap may be hinged out;

Fig. 4 is a fragmentary detail of the toggle; and

Fig. 5 is a horizontal section taken at one 35 corner of the car.

The car body has fixed ends 2 and movable sides. Each of the latter comprises two sections 3 and 4, extending the full length or substantially the full length of the car, 3 40 being the upper section and 4 the lower section. These sections are mounted to slide vertically in suitable end guides 5, and when closed abut at their adjacent edges, substantially midway of the height of the car body.

45 The sections are connected at each end by a cable 6, one end of which is connected at 7 to the lower part of the upper section, the cable thence passing upward to and over a pulley 8 near the top of the car, and thence 50 downward to the upper part of the lower section, to which it is attached at 9, other pulleys 10 and 11 guiding its lower course. It will thus be seen that the side of the car can be opened, either by pulling down the lower 55 section, which will force the upper section to rise, or by raising the upper section thus

permitting the lower section to descend by gravity. Conversely, the sections when opened can be closed, either by pulling down the upper section or by raising the lower. 60 The attachments 7 and 9 are preferably of such character, as indicated, as to permit the cable to be readily disengaged from either section, so that the sections may be removed.

The sections are additionally connected, at 65 one or both ends, by a toggle composed of bars 12 and 13, which in the closed condition lie horizontal, folded together at the meeting portions of the sections, which may be recessed at the inside, as shown at 14, to accommodate them without projection into the interior of the car. The toggle bars are pivoted to the respective side sections at 15 and 16, and their other ends are pivoted together at 17. The arrangement is preferably 70 such that when the sections are fully opened the toggle is straightened and its members carried slightly past center, in which condition it is prevented from flexing in the other direction by contact with the adjacent fixed 75 end portions of the car. Under these circumstances the toggle is locked and rigidly holds the side sections in their separated positions. A spring 18 may be provided at the hinge of the toggle to carry it automatically 80 the slight distance past center sufficient to insure it against collapse, when the car is opened.

As heretofore stated the upper section 3 is preferably heavier than the lower section, 90 so that when the toggle or toggles are broken, this section will automatically descend and will lift the lower section. It is not necessary that the overbalancing be great, and a toggle at one end will be sufficient, which will materially facilitate the closing of the car.

As shown the lower section 4 may have a horizontal hinge 19, which permits the lower portion 20 of this section to swing when it 100 passes downward below the slides in the opening of the car. Thus, this lower portion can be folded outward to avoid obstruction beneath, or to serve as an apron or gap closer, for example when loading to or from 105 the deck of a boat immediately alongside.

The car preferably has projecting eaves or roof extensions 21 at the sides, and these may be hinged as indicated at 22 so as to fold upward out of the way when the upper 110 sections 3 slide up. This result may be produced automatically by the sections, and the

eaves may be lowered automatically, by springs 23, when the sections descend again in closing.

No attempt has been made to show the particular structural arrangement of the fixed part of the car body. It will be understood that this may be substantially as usual, except that the end portions may be made stronger than ordinarily in order to compensate for absence of support along the sides. Or, as indicated at 24 in Fig. 1, one or more joists may be provided at the sides behind the slidable sections.

What I claim as new is:

- 15 1. A freight car having an entire side which opens, the same being composed of upper and lower sections which are slidably mounted for movement in opposite directions.
- 20 2. A freight car having a side comprising upper and lower sections, vertical slides whereon said sections are guided, and connections whereby said sections are caused to slide simultaneously in opposite directions.
- 25 3. A freight car having a side comprising upper and lower sections, vertical slides whereon said sections are guided, and cables and pulleys for the connection of the sections, said cables passing from the lower 30 part of the upper section over upper pulleys

and thence downward to the upper part of the lower section.

4. A freight car having a side comprising upper and lower sections, vertical slides whereon said sections are guided, and cable 35 connections causing said sections to slide in opposite directions, the upper section overweighting the lower section so that the sections tend to close.

5. A freight car having a side comprising 40 upper and lower sections, vertical slides whereon said sections are guided, cable connections causing said sections to slide in opposite directions, and a toggle for holding them open.

6. A freight car having an entire side which opens, the same being composed of upper and lower sections which are slidably mounted for movement in opposite directions, and a folding roof extension permitting the rise of the upper section. 50

7. A freight car having an entire side which opens, the same being composed of upper and lower sections which are slidably mounted for movement in opposite directions, and the lower section having its lower portion movable on a hinge when said section is lowered. 55
